FRACTURE REDUCTION APPARATUS

Joe J. Ettinger, Warsaw, Ind.

Application January 28, 1935, Serial No. 3,842

17 Claims. (Cl. 128—84)

This invention relates to surgical apparatus and has special reference to a fracture reduction apparatus, whereby skeletal traction may be obtained between the broken parts of a long bone such as, for instance, one of the lower leg bones.

One important object of this invention is to provide an improved device of this kind whereby adjustment may be made for the desired distances between the pins or wires extending through the broken bone.

A second important object of the invention is to provide novel means for supporting the pins and wires used in connection with the invention.

A third important object of the invention is to provide novel means for moving such pins and wires apart after they have been applied to the bone and secured in the apparatus.

A fourth important object of the invention is the provision of novel means whereby to adjust the height of one of such pins or wires relative to the other.

A fifth important object of the invention is to provide novel means whereby such pins or wires may be independently adjusted at desired angles to the horizontal and thus to each other.

A sixth important object of the invention is to provide novel means whereby such pins or wires may be swingingly adjusted to desired angular positions around vertical axes.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a perspective view of the complete apparatus.

Figure 2 is a section taken longitudinally of a base on its central vertical plane.

Figure 3 is a section on the line 3—3 of Figure 2.

Figure 4 is a longitudinal section through a telescopic tube forming part of the invention.

Figure 5 is a vertical section through the leg of a yoke used herein.

Figure 6 is a detail section on the line 6—6 of Figure 5.

Figure 7 is a longitudinal section through a pin and wire supporting sleeve used herewith.

In the embodiment of the invention herein shown there is provided a pair of hollow base members 10 supported on legs 11. To one of these

base members is secured the section 12 of a telescopic tube consisting of sections 12 and 13. This tube is preferably rectangular in cross section and the section 12 projects from a side of a base 10 adjacent the end thereof while the section 13 passes slidably through the corresponding part of the remaining base 10, the base being held in adjusted position on the tube 13 by a suitable set screw (not shown).

Extending vertically of each base 10 at the center thereof is a shaft 15 whereon is mounted a yoke consisting of a cross member 16 having a leg 17 at each end, the legs 17 being hollow and preferably rectangular in cross-section. By means of this construction the yokes may be rotated to desired angles relative to the bases 10, which latter are held parallel by the telescopic tube consisting of the sections 12 and 13.

Slidable vertically in each of the legs 17 is a post 18 having at its upper end a head 19. On the sides of these heads on each yoke which face the other yoke are pivotally mounted clamp blocks 20, the mounting being such as to permit the clamp blocks 20 to rotate to desired angular positions about horizontal axes. Each of these clamp blocks is provided with a vertical slot 21 extending downwardly from its upper side to receive a wire and pin supporting sleeve 22 which is held in adjusted positions in the slots by a set screw 23. A set screw 24 serves to hold the telescopic section 12 in engagement with its base 10.

Projecting from the lower part of one yoke and away from the other yoke is a pair of L-shaped brackets 26 connected at their upper ends by a downwardly curved cross member 27 provided with an arcuate slot 28 through which extends a pair of clamping screws 29 carrying at their inner ends a foot board 30. By loosening the screws 29 the foot board may be swung in a vertical plane extending parallel to the yoke and, when in desired position, may be securely clamped in swung position.

The means for swinging the yokes about their axes is shown in Figs. 2 and 3. As there shown there is fixed on the lower end of the shaft 15 a lever 31 having a yoke 32 the arms of which are provided with slots 33. Pins 34 projecting from a nut 35 extend into these slots so that the nut is permitted to move longitudinally of the lever 31 as the latter swings and also to assume different angular positions relative to said lever. A screw 36 is screwed through this nut and is journaled in the sides of the base 10, the screw being provided with collars 37 to prevent its longitudinal movement. One end of the screw 36 pro-

jects from the base 10 and is provided with rotating means such as the crank 38. Thus by rotating the screw the lever 31, and consequently the yoke, is swung to desired position, both yoke 5 and lever being fixed on the shaft.

Fig. 4 shows the manner of adjusting the telescopic members 12 and 13 relative to each other. From this Fig. 4 it will be seen that the member 12 has the end which projects into the member 10 13 closed at 39 except for a threaded opening 40 wherethrough is threaded a screw 41 which has a reduced end 42 which projects through an opening in the closed end 43 of the member 13, the projecting end having a crank provided head 44 15 fixed thereon so that, as the screw is rotated the members 12 and 13 telescope to compact or expanded position.

Similarly each member 18 is slid, as shown in Fig. 5, up and down in its leg 17, a tube 45 being 20 held in the leg 17 by a pin 46 and having an internally threaded neck 47 wherein is threaded a screw 48 having a reduced upper end which passes through an opening in the otherwise closed upper end of the member 18, the projecting end 25 of 48 having a crank provided head 49 fixed thereon.

From Fig. 6 it will be seen that the clamp 20 is pivotally mounted on the head 19 by a pin 50.

In Fig. 7 is shown the detail construction of 30 the sleeves 22 and will be seen that one end of the sleeve has a relatively large bore 51 to support a Steinman pin while the other end is provided with a small bore to accommodate a Kirschner wire, the wire being stretched by a 35 tractor such as is shown and described in my prior application, Serial Number 643,101, and bearing Patent No. 1,967,471 dated July 24, 1934. It is, of course, to be understood that the Kirschner wire is retained in the tractor during 40 adjustment of the splint to the injured limb and that the distance between the legs of the tractor is so arranged that the wire may slide through the members 22 during such adjustment thus permitting various angular positions of the wire. 45 Also, when Steinman pins are used the sleeves 22 are so adjusted in the clamps that sliding movements of the pins may take place during the adjustment of the splint.

By means of the adjustment of the telescopic 50 tube traction may be exerted on a broken bone through spaced points of which has been passed a pair of Steinman pins or Kirschner wires. Also the yokes may be angularly adjusted with respect to each other in a horizontal plane to 55 obtain the correct lateral tractive direction and the pins or wires may be adjusted to suitable vertical angles to effect such rotative movement of one fragment of the broken bone to the other as will bring these fragments into normal relation.

Such procedure avoids all improper relation 60 between the proximal and distal fragments of the broken bone so that a cast may be applied after which the splint may, if desired, be removed, the cast itself holding the sleeves 22 in proper position.

There has thus been provided a simple and 70 efficient device of the kind described and for the purpose specified.

It is obvious that minor changes may be made 75 in the form and construction of the invention without departing from the material spirit thereof. It is not, therefore, desired to confine the invention to the exact form herein shown and

described, but it is desired to include all such as properly come within the scope claimed.

Having thus described the invention, what is claimed as new, is:

1. In a fracture reduction apparatus, a pair of bases, a pair of telescopically nested tubes connecting said bases, means to expand and contract the telescopic tubes, an upstanding yoke on each base having clamp means at the upper ends of its arms, vertical shafts journaled in said bases and having the yokes fixed thereto, and said bases being in the form of inverted channels and said shafts projecting downwardly into said channels, an arm fixed to the lower end of each shaft and projecting along the channel, a yoke on the free end of each arm, a nut held in said yoke and having pin and slot connection therewith, and an adjusting screw journaled in the sides of the channel and screwed through said nut.

2. In a fracture reduction apparatus, a pair of bases, a pair telescopically nested tubes connecting said bases, means to expand and contract the telescopic tubes, an upstanding yoke on each base having clamp means at the upper ends of its arms, one of said bases being slidable along one of the telescopic tubes, means to secure the last mentioned base in adjusted position on its tube, vertical shafts journaled in said bases and having the yokes fixed thereto, and said bases being in the form of inverted channels and said shafts projecting downwardly into said channels, an arm fixed to the lower end of each shaft and projecting along the channel, a yoke on the free end of each arm, a nut held in said yoke and having pin and slot connection therewith, and an adjusting screw journaled in the sides of the channel and screwed through said nut.

3. In a fracture reduction apparatus, a pair of bases, a pair of telescopically nested tubes connecting said bases, means to expand and contract the telescopic tubes, an upstanding yoke on each base including a pair of vertically extending hollow arms and extension members telescopically mounted in said arms, clamp members at the upper ends of said extension members, and means to cause protrusion and retraction of the extension members in their arms.

4. In a fracture reduction apparatus, a pair of bases, a pair of telescopically nested tubes connecting said bases, means to expand and contract the telescopic tubes, an upstanding yoke on each base including a pair of vertically extending hollow arms and extension members telescopically mounted in said arms, clamp members at the upper ends of said extension members, means to cause protrusion and retraction of the extension members in their arms, one of said bases being slidable along one of the telescopic tubes, and means to secure the last mentioned base in adjusted position on its tube.

5. In a fracture reduction apparatus, a pair of bases, a pair of telescopically nested tubes connecting said bases, means to expand and contract the telescopic tubes, an upstanding yoke on each base including a pair of vertically extending hollow arms and extension members telescopically mounted in said arms, clamp members at the upper ends of said extension members, means to cause protrusion and retraction of the extension members in their arms, vertical shafts journaled in said bases and having the yokes fixed thereto, and means to effect rotation of said shafts whereby to vary the angular relation of the yokes and bases.

6. In a fracture reduction apparatus, a pair of

bases, a pair of telescopically nested tubes connecting said bases, means to expand and contract the telescopic tubes, an upstanding yoke on each base including a pair of vertically extending hollow arms and extension members telescopically mounted in said arms, clamp members at the upper ends of said extension members, means to cause protrusion and retraction of the extension members in their arms, one of said bases being 10 slidable along one of the telescopic tubes, means to secure the last mentioned base in adjusted position on its tube, vertical shafts journaled in said bases and having the yokes fixed thereto, and means to effect rotation of said shafts whereby to vary the angular relation of the yokes and bases.

7. In a fracture reduction apparatus, a pair of bases, a pair of telescopically nested tubes connecting said bases, means to expand and contract the telescopic tubes, an upstanding yoke on each base having clamp means at the upper ends of its arms, vertical shafts journaled in said bases and having the yokes fixed thereto, said bases being in the form of inverted channels and said shafts projecting downwardly into said channels, 25 an arm fixed to the lower end of each shaft and projecting along the channel, a yoke on the free end of each arm, a nut held in said yoke and having pin and slot connection therewith, an adjusting screw journaled in the sides of the channel and screwed through said nut and horizontally arranged pivot means rotatably connecting the clamp means to the upper ends of said arms.

8. In a fracture reduction apparatus, a pair of bases, a pair of telescopically nested tubes connecting said bases, means to expand and contract the telescopic tubes, an upstanding yoke on each base having clamp means at the upper ends of its arms, one of said bases being slidable along one of the telescopic tubes, means to secure the last mentioned base in adjusted position on its tube, vertical shafts journaled in said bases and having the yokes fixed thereto, said bases being in the form of inverted channels and said shafts projecting downwardly into said channels, an 40 arm fixed to the lower end of each shaft and projecting along the channel, a yoke on the free end of each arm, a nut held in said yoke and having pin and slot connection therewith, an adjusting screw journaled in the sides of the channel and screwed through said nut and horizontally arranged pivot means rotatably connecting the clamp means to the upper ends of said arms.

9. In a fracture reduction apparatus, a pair of bases, a pair of telescopically nested tubes connecting said bases, means to expand and contract the telescopic tubes, an upstanding yoke on each base including a pair of vertically extending hollow arms and extension members telescopically mounted in said arms, clamp members at the upper ends of said extension members, means to cause protrusion and retraction of the extension members in their arms, and horizontally arranged pivot means rotatably connecting the clamp means to the upper ends of said extension members.

10. In a fracture reduction apparatus, a pair of bases, a pair of telescopically nested tubes connecting said bases, means to expand and contract the telescopic tubes, an upstanding yoke on each base including a pair of vertically extending hollow arms and extension members telescopically mounted in said arms, clamp members at the upper ends of said extension members, means to cause protrusion and retraction of the extension members in their arms, one of said bases

being slidable along one of the telescopic tubes, means to secure the last mentioned base in adjusted position on its tube, and horizontally arranged pivot means rotatably connecting the clamp means to the upper ends of said extension members.

11. In a fracture reduction apparatus, a pair of bases, a pair of telescopically nested tubes connecting said bases, means to expand and contract the telescopic tubes, an upstanding yoke on each base including a pair of vertically extending hollow arms and extension members telescopically mounted in said arms, clamp members at the upper ends of said extension members, means to cause protrusion and retraction of the extension members in their arms, vertical shafts journaled in said bases and having the yokes fixed thereto, means to effect rotation of said shafts whereby to vary the angular relation of the yokes and bases, and horizontally arranged pivot means rotatably connecting the clamp means to the upper ends of said extension members.

12. In a fracture reduction apparatus, a pair of bases, a pair of telescopically nested tubes connecting said bases, means to expand and contract the telescopic tubes, an upstanding yoke on each base including a pair of vertically extending hollow arms and extension members telescopically mounted in said arms, clamp members at the upper ends of said extension members, means to cause protrusion and retraction of the extension members in their arms, one of said bases being slidable along one of the telescopic tubes, means to secure the last mentioned base in adjusted position on its tube, vertical shafts journaled in said bases and having the yokes fixed thereto, means to effect rotation of said shafts whereby to vary the angular relation of the yokes and bases, and horizontally arranged pivot means rotatably connecting the clamp means to the upper ends of said extension members.

13. In a fracture reduction apparatus, a pair of bases, a pair of telescopically nested tubes connecting said bases, means to expand and contract the telescopic tubes, an upstanding yoke on each base including a pair of vertically extending hollow arms and extension members telescopically mounted in said arms, clamp members at the upper ends of said extension members, means to cause protrusion and retraction of the extension members in their arms, horizontally arranged pivot means rotatably connecting the clamp means to the upper ends of said extension members, and a foot board swivelly mounted on one of said yokes.

14. In a fracture reduction apparatus, a pair of bases, a pair of telescopically nested tubes connecting said bases, means to expand and contract the telescopic tubes, an upstanding yoke on each base including a pair of vertically extending hollow arms and extension members telescopically mounted in said arms, clamp members at the upper ends of said extension members, means to cause protrusion and retraction of the extension members in their arms, one of said bases being slidable along one of the telescopic tubes, means to secure the last mentioned base in adjusted position on its tube, horizontally arranged pivot means rotatably connecting the clamp means to the upper ends of said extension members, and a foot board swivelly mounted on one of said yokes.

15. In a fracture reduction apparatus, a pair of bases, a pair of telescopically nested tubes con-

necting said bases, means to expand and contract the telescopic tubes, an upstanding yoke on each base including a pair of vertically extending hollow arms and extension members telescopically mounted in said arms, clamp members at the upper ends of said extension members, means to cause protrusion and retraction of the extension members in their arms, vertical shafts journaled in said bases and having the yokes fixed thereto, means to effect rotation of said shafts whereby to vary the angular relation of the yokes and bases, horizontally arranged pivot means rotatably connecting the clamp means to the upper ends of said extension members, and a foot board 10 swivelly mounted on one of said yokes.

16. In a fracture reduction apparatus, a pair of bases, a pair of telescopically nested tubes connecting said bases, means to expand and contract the telescopic tubes, an upstanding yoke on each base including a pair of vertically extending hollow arms and extension members telescopically mounted in said arms, clamp members at the upper ends of said extension members, means to

cause protrusion and retraction of the extension members in their arms, one of said bases being 5 slidable along one of the telescopic tubes, means to secure the last mentioned base in adjusted position on its tube, vertical shafts journaled in said bases and having the yokes fixed thereto, means to effect rotation of said shafts whereby to vary the angular relation of the yokes and bases, horizontally arranged pivot means rotatably connecting the clamp means to the upper ends of 10 said extension members, and a foot board swivelly mounted on one of said yokes.

17. In a fracture reduction apparatus, a pair of bases, a pair of telescopically nested tubes connecting said bases, means to expand and contract 15 the telescopic tubes, an upstanding yoke on each base having clamp means at the upper ends of its arms, and a tubular member clamped in each of said clamp means and having a relatively large bore at one end and a relatively small 20 bore at the other end forming a continuation of said large bore.

JOE J. ETTINGER.
